DESIGN FOR A RING OR THE LIKE

George F. Jordan, New Dorp, N. Y.

Application August 11, 1941, Serial No. 102,789

Term of patent 7 years

To all whom it may concern:

Be it known that I, George F. Jordan, a citizen of the United States, residing in the town of New Dorp, county of Richmond, and State of New York, have invented a new, original, and ornamental Design for a Ring or the like, of which the following is a specification, reference being had to the accompanying drawing forming a part thereof.

What I claim is:

The ornamental design for a ring or the like, as shown.

GEORGE F. JORDAN.
